UNITED STATES PATENT OFFICE.

ADELMEER M. BATES AND ALBERT KRASA, OF CHICAGO, ILLINOIS, ASSIGNEES TO
BATES VALVE BAG COMPANY, OF CHICAGO, ILLINOIS, A CORPORATION OF WEST
VIRGINIA.

TRIMMER FOR SEWING MACHINES.

Application filed January 26, 1924. Serial No. 688,724.

To all whom it may concern:

Be it known that we, ADELMEER M. BATES and ALBERT KRASA, citizens of the United States, and residents of Chicago, in the county of Cook and State of Illinois, have invented a new and useful Trimmer for Sewing Machines, which invention is fully set forth in the following specification.

Our invention relates to a trimmer for sewing machines, and has for its object to provide such a trimmer that may be easily applied to the ordinary sewing machine and that will operate efficiently and accurately.

In the accompanying drawings, forming a part of this specification, Fig. 1 shows a side elevation of our trimmer with portions of the sewing machine to which it is attached. Fig. 2 shows a plan view of the trimmer mechanism, and Fig. 3 is an end elevation of the same.

The trimming mechanism is shown as attached to a sewing machine having the usual overhanging arm 4 and needle operating lever 5, with a needle bar 6 operating in guides 7, one of which is shown. A block 8, fastened on the needle bar, is connected by a link 9 to the operating end of the lever 5. These parts form no portion of our invention and are shown merely to indicate the relation of our trimmer to the usual parts of a sewing machine.

The trimming mechanism comprises a stationary knife 10, fixed in the throat plate 11. The cutting edge of the knife rises from the throat plate in the direction of travel of the work, as shown in Fig. 3. A co-operating knife 12 has an edge slanting in the opposite direction and adapted to co-operate with the knife 10 to accomplish a shearing cut. The knife 12 is mounted in a knife carrier 13, fastened on the end of a slide 14. A guide block 15, for guiding the slide, may be fastened by means of a bracket 16 to the overhanging arm 4. A block 17 is fastened to the upper end of the slide 14 and is connected by a link 18 to a lever 19, mounted on a fulcrum pin 20, supported by a bracket 21, which may be attached to the overhanging

arm 4. The opposite end of the lever 19 carries a fork 22, which embraces a block 23, 50 operated by a pin 24, mounted in the needle-operating lever not far from its fulcrum 25.

The guide 15 is pivoted upon a pin 26, carried by the bracket 16. A spring 27 connects an upwardly-extending lug 28 on the guide 15 to a hook 29, extending from a collar 30 about the fulcrum pin 20. In this way, the spring 27 tends to rock the guide 15 about the pivot 26, so as to hold the knife 12 against the knife 10. The pin 24 is near enough the fulcrum 25 so that the two knives, 10 and 12, remain constantly in contact, and the reciprocating motion given to the knife 12 in synchronism with the reciprocation of the needle results in a shearing cut of the work while it is at rest during each needle stroke.

This trimmer is an improved form of that disclosed in a prior application of Adelmer M. Bates for cutter for sewing machines, filed April 20, 1922, Serial No. 555,663.

What we claim is:

1. A trimmer for sewing machines, comprising a knife, a carrier for the knife, means to reciprocate the carrier in a direction substantially perpendicular to the knife edge, a guide for the carrier pivoted about an axis substantially parallel with the knife edge, and a spring tending to turn the guide about its pivot to press the knife against a co-operating shearing edge.

2. A trimmer for sewing machines, comprising a stationary knife having its cutting edge substantially in line with the travel of the work, a co-operating knife, a slide carrying said co-operating knife, a guide for the slide pivoted on an axis substantially parallel with the travel of the work, and a spring tending to turn the guide about its pivot in a direction to hold the movable knife against the stationary knife in shearing relation thereto.

3. In a sewing machine, a needle bar, a knife-carrying slide substantially parallel with said bar, a lever having one arm connected to said bar, a lever having one arm

connected to said slide, the two levers being substantially parallel and the fulcrum of the needle-bar-actuating lever being more distant from the bar than is the fulcrum of the knife-actuating lever from the knife slide, and a connection between an arm of

needle-actuating lever on the side of the fulcrum of the needle-actuating lever distant from the needle bar.

10

In testimony whereof, we have hereunto signed our names to this specification.

ADELMER M. BATES.
ALBERT KRASA.
